UNITED STATES PATENT OFFICE.

LESLIE A. BROWN, OF WALLINGFORD, CONNECTICUT, ASSIGNOR TO R. WALLACE & SONS MFG. CO., OF WALLINGFORD, CONNECTICUT, A CORPORATION.

DESIGN FOR A SECTIONAL BORDER.

46,083.

Specification for Design.

Patented July 14, 1914.

Application filed May 11, 1914. Serial No. 837,946. Term of patent 7 years.

To all whom it may concern:

Be it known that I, LESLIE A. BROWN, a citizen of the United States, residing at Wallingford, in the county of New Haven and State of Connecticut, have invented a new, original, and ornamental Design for Sectional Borders, of which the following is a specification, reference being had to the accompanying drawing, forming part thereof.

The figure is a perspective view of a sectional border embodying my design.

I claim:

The ornamental design for a sectional border, as shown.

LESLIE A. BROWN.

Witnesses:

HENRY L. WALLACE,
B. W. TOWNSEND.
